John E. Small

UNITED STATES PATENT OFFICE.

JOHN E. SMALL, OF BERLIN, WISCONSIN.

IMPROVED CRIB AND CHAIR.

Specification forming part of Letters Patent No. 59,087, dated October 23, 1866.

To all whom it may concern:

Be it known that I, JOHN E. SMALL, of the city of Berlin, county of Green Lake, and State of Wisconsin, have invented a new and useful article of household furniture, which I call a "Combined Crib and Rocking-Chair;" and I do hereby declare the following to be a full and exact description of the construction and operation thereof, reference being had to the accompanying drawings, and the letters of reference marked thereon, which said drawings and letters are hereby made a part of this specification.

In constructing this article I make the back, the seat, the legs, and the rockers the same as in an ordinary rocking-chair.

The arms (marked *a a* in the drawings) are allowed to drop by means of the joints *b b*. To these arms I attach folding racks, (marked *c c* in the drawings.) These racks may be raised when the arms are dropped, the arms thus forming portions of the bottom, and the racks *c c* forming the railing of the ends of a child's crib or cradle. I also attach pieces of leather, cloth, or other equivalent material from the back of the chair to the pieces *c c*, as

seen at *d d* in the drawings, thus inclosing one side of the cradle. I next attach to the front of the seat the folding side piece or rack (marked *e* in the drawings) by means of dowel-pins fixed in the rack and inserted in the seat at *fff*. The whole is then ready for use as a crib or cradle. If it is desired to use this article as a rocking-chair, I fold the parts *c c* to the arms *a a*, raise the arms upright, and fasten them to the back of the chair by means of springs, bolts, hooks, or other equivalent device, as seen at *i i i* in the drawings. I then disengage the side piece, *e*, from the seat and place it out of the way under the seat, fastening it there by means of a button attached to the bottom, or by any other equivalent device.

I claim—

The joints *b b*, in combination with the end racks, *c c*, the folding side rack, *e*, and the pieces *d d*, substantially as and for the purpose set forth.

JOHN E. SMALL.
